CAN OPENER

Thomas A. Long, Hammond, Ind.

Application September 4, 1944, Serial No. 552,585

7 Claims. (Cl. 30—15)

1 A considerable effort has been extended heretofore in making can openers more reliable and satisfactory. The most satisfactory ones have been those which included a crank carried by a bracket extending out from a wall or other mounting surface. In addition to the crank, such can openers included a piercing lever which moved the cutting blade to produce the initial cutting of the can. It has been recognized that the extending bracket was sometimes objectionable and various expedients have been worked out for minimizing this objection, as for example, by having the bracket swing into parallelism with the wall when not in use.

One object of the present invention is to provide a satisfactory can opener which operates entirely by movement of the crank. This movement operates the cutter blade to cause the initial piercing of the can as well as rotating the can against the cutter blade. This is accomplished according to the preferred form of the present invention by arranging a pin on the crank which is so disposed as to engage a lever operating the cutter blade. The initial movement of the crank actuates the cutter blade which is then held out of engagement with the pin by the pressure of the rotating can thereon as the crank continues to be rotated to turn the can. Reverse rotation of the crank withdraws the cutter blade from the can.

Another object of the invention is to completely eliminate the objectionable extending bracket. This is accomplished by the extremely simple expedient of putting the crank and the cutter on the same side of the supporting plate and locating them sufficiently far apart so that the can does not interfere with the rotation of the crank. Of course the knurled wheel driving the can is driven by a train of gears or the like. This might seem to be introducing complications which would be too expensive, but gears for this purpose can be simple stampings and hence the cost is not prohibitive. Furthermore, the gearing can give a mechanical advantage to the crank which permits using a fairly short crank and still having it turn easily enough to be operated from any position.

Another object of the invention is to provide a can opener which is suitable for mounting on a hinged door, such as the door of the cabinet in which the cans are kept. According to the present invention, this is accomplished largely by the feature last mentioned and by keeping the entire assembly quite close to the surface on which it is mounted. The result is that when a

2 can opener is mounted on a hinged door, the plane of rotation of the handle coincides nearly enough with the pivotal axis of the hinge of the door so that turning of the handle produces very little torque tending to swing the door. Hence the door may be kept steady either by a very little force applied with the other hand, or by pressing it to the fully opened position so that a slight axial pressure on the handle of the crank holds the door pressed against the adjacent wall or other stop. The compactness of the opener also keeps it from taking up any objectionable amount of space within the cabinet when the door is closed.

15 Additional objects and advantages will be apparent from the following description and from the drawing in which:

Fig. 1 is a front elevational view of the form of the invention chosen for illustration;

20 Fig. 2 is a vertical, sectional view taken approximately on the line 2—2 of Fig. 1;

Fig. 3 is a view corresponding to Fig. 1 but showing the position of the parts after the crank has been turned slightly more than one revolution;

25 Fig. 4 is a fragmentary, side elevational view of a modification of the invention.

Although the law requires a full and exact description of at least one form of the invention, 30 such as that which follows, it is, of course, the purpose of a patent to cover each new inventive concept therein no matter how it may be disguised by variations in form or additions of further improvements; and the appended claims 35 are intended to accomplish this purpose by particularly pointing out the parts, improvements, or combinations in which the inventive concepts are found.

In the illustrated form of the invention, the 40 can opener includes a knurled drive wheel 10, cutter blade 11 and a crank 12 all of which are carried by a base plate 13 having suitable perforations 14 for receiving mounting screws. The crank 12 drives a pinion 16 rigid therewith which 45 in turn drives idler pinions 17, the last of which drives pinion 18 which in turn drives knurled wheel 10 which is rigid therewith. The crank 12 bears a pin 21 which engages the upper end of lever 22, the lower end of which forms the cutting blade 11.

The operation of the can opener is as follows: 50 The starting position is shown in Fig. 1. A can 23 is slipped under the cutter blade 11 and rested with its rim on knurled roller 10. The operator 55 then grasps the handle 24 of crank 12 and rotates

the crank. Near the end of the first revolution, the pin 21 strikes the lever 22 near its upper end and urges it in a counterclockwise direction to press the cutter blade 11 down through the cap of the can to the position shown in Fig. 3. The pin 21 then slips past the lever 22, the movement of which is limited by a stop pin 26. The rotation of the knurled wheel 10 turns the can forcing it to rotate against cutting blade 11, thus cutting the top of the can around the periphery thereof. The pressure of the can against cutting blade 11 holds the lever 22 against the pin 26. When the can cover has been slit the desired distance around its periphery, the crank 12 is turned in the reverse direction. The initial turning of the crank in the reverse direction rotates the can slightly in the reverse direction applying a force against the back and side of the cutter blade 11 to urge it in the clockwise direction and move it at least far enough so that the pin 21 moving in counterclockwise direction will engage the left side of lever 22 and press the lever in a clockwise direction to move the parts back to the starting position shown in Fig. 1. Further clockwise movement of the lever 22 may be prevented by a stop 21. Optionally the stop 21 could be resiliently yieldable so that pressure on the handle 24 would raise the cutter blade 11 a little higher than shown in Fig. 1 so as to more completely release the can.

The parts will stay in the position shown in Fig. 1 until the crank 12 is again actuated and hence the can opener is ready to receive another can.

It is thus seen that manipulation of the single lever or crank 12 performs the whole job. Furthermore, it will be observed that the plane of rotation of the crank 12 is so close to the mounting surface that very little torque will be exerted by any position in this surface. This makes it practicable to use a hinged door as support member and also completely eliminates any such trouble as pulling out of screws or bending of parts which sometimes previously resulted from the leverage supplied by the bracket extending outwardly from the wall in past can openers.

It is believed that all of the details will be sufficiently evident from the drawing. It may be noted, however, that the various pinions or gears may be stamped from sheet metal so that their cost is extremely low. Also they are simple spur gears of uniform thickness so that if it were desired to cut them for greater accuracy, they could be gang-cut. The crank 12 may be made rigid with the pinion 16 by means of a threaded stud 31 which may be rigid with either the crank or the pinion and threaded into the other washers 32 forming the necessary spacers, and the washer 33 also forming a bearing member for bearing engagement with the base plate 13. The assembly of pinion 18 and knurled wheel 10 is similar except that the larger washer 32 is not required and the threads on stud 34 are left-handed while those on stud 31 are right-handed. As a matter of fact, studs 31 and 34 can be threaded to both members instead of having a rigid engagement with one if preferred.

If a cutting wheel 41 is preferred to a stationary cutting blade, it may be mounted at the bottom of lever 22, as seen in Fig. 4.

The hardest part of can opening heretofore has usually been the initial piercing of the can. This is quite easy in the present invention. The lever 22 gives a mechanical advantage of nearly three to

one and the crank 12 gives a mechanical advantage of nearly four to one. These mechanical advantages are multiplied so that not much more than one-twelfth the force required at the point of piercing need be applied to the handle 24, ignoring friction.

I claim:

1. A can opener including a lever of the first class having arms of unequal length; a cutter blade positioned at the free end of the shorter arm, a drive wheel for turning the can against the cutter blade, a crank for turning the drive wheel, and means responsive to the turning of the crank for engaging the longer arm to swing the same, thereby causing the cutter blade to pierce the can.
2. A can opener including a base plate, a crank pivotably carried thereby on one side thereof, a cutter blade carried on the same side of the base plate, and a drive wheel rotatably carried by the base plate and on the same side thereof, adapted to turn a can against the cutter blade and driven by said crank.
3. A can opener including a base plate, a crank pivotably carried thereby on one side thereof, a cutter blade carried on the same side of the base plate, and a drive wheel rotatably carried by the base plate and on the same side thereof, adapted to turn a can against the cutter blade and driven by said crank.
4. A can opener including a base plate, a crank pivotably carried thereby on one side thereof, a cutter blade carried on the same side of the base plate, and a drive wheel rotatably carried by the base plate and on the same side thereof adapted to turn a can against the cutter blade and driven by said crank through gears.
5. A can opener including a base plate, a crank pivotably carried thereby on one side thereof, a cutter blade carried on the same side of the base plate, and a drive wheel rotatably carried by the base plate and on the same side thereof, adapted to turn a can against the cutter blade and driven by said crank, said crank being pivotal about an axis above and substantially further from the drive wheel than the length of the crank.
6. A can opener including a base plate, a crank pivotably carried thereby on one side thereof, a cutter blade carried on the same side of the base plate, and a drive wheel rotatably carried by the base plate and on the same side thereof, adapted to turn a can against the cutter blade and driven by said crank, said crank being pivotal about an axis above and substantially further from the drive wheel than the length of the crank and being connected to the drive wheel through speed reducing means to reduce the torque required to turn the crank.
7. A can opener including a cutter blade carried by a pivoted lever of the first class, a drive wheel rotatable in one direction for turning the can against the cutter blade, a crank for turning the drive wheel in said direction, a projection on said crank adapted, when the crank is turned to rotate the drive wheel in said direction, to engage said lever and pivot it in the opposite direction to pierce the can with the cutter blade, the movement of the can against the cutter blade then urging the lever further in the same direction, and the projection then clearing the lever.

THOMAS A. LONG.
